FABRIC EDGE-FOLDING AND PRESSING DEVICE

Jacob Silverman, New York, N. Y.

Application July 2, 1941, Serial No. 400,803

1 Claim. (Cl. 223—38)

This invention relates to portable edge folding and pressing machines being particularly adapted to form patch pockets and like articles.

Machines for the above general purpose are well known but require the use of both hands of the operator in their operation. Such machines are usually provided with means for clamping the article worked on entailing the use of one operating handle and are also provided with edge folding means entailing the use of another operating handle. In addition, foot operated means are provided for the application of heat and pressure. Such machines keep both hands of the operator occupied until the operation is completed so that the handles may be released.

In the interest of expediting and speeding up the operation, the present invention contemplates the provision of a machine of the indicated character in which the clamping of the work and the folding of its edges occurs sequentially by the operation of a single handle leaving one of the operator's hands free for preparing another piece of work for the machine.

The invention also contemplates means including the pressing parts of the machine for holding the machine parts in pressing relation whereby both hands of the operator are freed for other functions.

The invention further seeks to provide a machine of the character indicated, of novel mechanical design and arrangement and of simple structure.

The foregoing advantages, features, and purposes of the invention and others which will become apparent from the following detailed specification, are exemplified in the embodiment illustrated in the accompanying drawings, said drawings forming the bases for said specification.

In the drawings:

Fig. 1 is a plan view of a machine incorporating the invention.

Fig. 2 is a vertical longitudinal sectional view thereof.

Fig. 3 is an enlarged plan view of the machine table showing the edge folding means.

Fig. 4 is a vertical transverse sectional view of the machine.

Fig. 5 is a fragmentary edge view of a portion of the edge folding means.

Fig. 6 is a plan view of a work blank before folding.

Fig. 7 is a similar view of said work blank after folding.

In that embodiment of the invention which

is illustrated, the machine comprises a support frame 10 for a table base plate 11 which is formed with an opening 12 shaped in accordance with the shape of a work blank 13 shown in Fig. 6. This blank is somewhat larger than the opening 12 as will be later understood.

The table base plate 11 has superimposed upon it a table top 14, said latter member being preferably spaced from the plate 11 as at 15. An opening 16, similar to the opening 12, is provided in the table top 14.

The edge folding means employed in the machine is disposed between the plate 11 and the table top 14 and, in the present instance, comprises folding plate members 17 and 18 and a pusher plate 19. In their normal position, as shown by the full lines of Fig. 3, the members 17 and 18 have their inner lateral edges 20 and 21 coincidental with the lateral edges of the openings 12 and 16. The inner edges 22 and 23 of said members 17 and 18 are also coincidental with the related edges of said openings 12 and 16.

The transverse leg portions 24 and 25 of the respective members 17 and 18 are preferably overlapped as at 26 and each of said leg portions is reduced in thickness to provide the relatively thinner parts 27 and 28 whereby they may fit in the space 15 without binding.

30 The folding plate members 17 and 18 are preferably mounted as on studs 29 carried by the table base plate 11. Said studs are engaged in cam slots 30 which guide the movement of the plate members as will be later described. 35 Spring means, such as shown at 31, are provided for urging the plate members into the normal position shown in Fig. 3.

The pusher plate 19 is preferably guided on guide studs 32 carried by the base plate 11, said 40 studs being engaged in slots 33 formed in said pusher plate. An edge of said latter plate is arranged to protrude beyond the forward edges of the plate 11 and the table top 14. Spring means, such as shown at 35, may be provided for

45 maintaining the pusher plate in projected position as shown in Fig. 3. As best seen in this figure, the folding plate members 17 and 18 are each preferably formed with angled corner edges 36 which are engaged by similarly angled edges 37 formed on the pusher plate 19. It is evident that when the pusher plate 19 is moved toward the left, the plates 17 and 18 will both move toward the left and toward each other. The dot-dash lines of Fig. 3 show the extent of this move-

50 ment.

Means are provided for guiding the positioning of a work blank, such as 13, with respect to the opening in the table top. In the present form this means comprises guide walls 38 mounted on the table top as best seen in Fig. 1.

The machine is provided with a work blank clamping plate 39 which also is the member about which the edge folds are made. This plate is shaped in accordance with the shape of the openings 12 and 16 and is somewhat smaller than said openings so as to move freely therethrough. The plate 39 is preferably mounted upon a relatively thick metal plate 30, which through spacer blocks 41 is carried, by means such as the studs 42, by a lever 43 pivoted, as at 44, to the machine frame 10. Slight relative movement is afforded between the lever 43 and the parts 39, 40 and 41 by making the holes 45, through which the studs 42 project, somewhat oversize as shown best in Fig. 2.

The free end of the lever 43 pivotally carries at 46 a pusher plate operating arm 47 which is provided with an operating handle 48. Spring means such as 49 is provided to hold the arm 47 normally out of operating engagement with the pusher plate 19. Spring means 50 is preferably provided for maintaining the lever 43 in an elevated position as can be well understood. An adjustment 51 for the latter spring is provided so that its tension may be regulated to elevate the lever 43 and yet be less than the tension of the spring 49. It can be seen that by this arrangement, depression of the handle 48 will first move the lever 43 on its pivot 44 to clamp a work blank and that continued movement of said handle will stretch the spring 49 and bring the arm 47 into operating engagement with the pusher plate 19.

The machine is provided with means for applying heat and pressure to the work blank. In its present form this means is preferably foot operated as by a pedal (not shown) connected by a member 52 to a lever 53. This lever is pivotally mounted upon a stud 54 secured to a transverse frame member 55. Another frame member 56 carries a stud 57. The studs 54 and 57 form guides for a plate 58 which is engaged by the nose 59 of the lever 53. Depressing the member 52 will cause the nose 59 to raise the plate 58, the lever 53 fulcruming on the stud 54.

A pressing or ironing plate 60 is provided, said plate being supported upon studs 61 carried by the plate 58. This condition holds true when pressure is being applied. Normally, however, the ironing plate 60 rests upon the frame member 56 and upon studs 62 carried by the frame member 55.

The ironing plate is heated as by means of an electrical heater 63 which is supplied by conductors 64 with electric current brought to terminals 65 by a suitable plug (not shown).

In operation, the levers 43 and 53 both being raised, a work blank such as 13 is placed to cover the opening 16 in the table top, the walls 38 guiding the positioning thereof. The handle 48 is depressed. Inasmuch as the spring 49 is stronger than the spring 50, the lever 43 and the arm 47 move as a unit until the plate 39 clamps the work blank 13 against the ironing plate 60 which at that time rests upon the member 56 and the studs 62. The peripheral portions of the blank assume a position at right angles to the body thereof because of their engagement with the edges of the openings 12 and 16. Continued pressure on the handle 48, will overcome the spring 49 to bring the arm 47 into engagement with the edge 34 of the pusher plate 19 which is thus moved to the left as shown in Fig. 2 to cause the folding plates 17 and 18 to fold the mentioned peripheral blank portions about the edges of the clamp plate 39. Figs. 2 and 4 show this condition. The lever 53 is then depressed by foot to raise the ironing plate upwardly against the pressure exerted on the handle 48. This foot pressure serves to wedge the folding plates 17 and 18 in their contracted position whereby pressure on the handle 48 may be released. So long as the foot pressure is maintained the clamping, edge folding, and pressing or ironing parts will maintain their positions as shown in Fig. 2 to leave both hands of the operator free to prepare a work blank for the next operation.

Upon release of the foot pressure, the ironing plate will drop back to its normal supports so that the springs 31 and 35 can become effective to restore the folding plates to their normal retracted position. The clamp plate 39 being released, the spring 50 becomes effective to raise it and the lever 48.

The work piece 13, with its edges folded about the plate 39, is raised with that plate and may easily be stripped therefrom. The finished work piece is shown at Fig. 7.

From the foregoing it can be seen that a simple, portable, efficient, and compact machine has been provided in which the objects of the invention are realized. It also is evident that, depending upon the work to be done, changes in arrangement, design, and proportion may well be made within the concept of the invention as exemplified by the machine described herein.

What I claim as new and desire to secure by Letters Patent, is:

In a machine of the character described, an operating handle, an edge fold mechanism actuator secured to said handle, an operating lever pivotally carrying said actuator and said handle, a clamp plate carried by said lever, and spring means connecting said lever and said actuator.
